UNITED STATES PATENT OFFICE.

WRIGHT SMITH, OF PATERSON, NEW JERSEY.

DESIGN FOR PATTERN FOR A HANDKERCHIEF.

SPECIFICATION forming part of Design No. 11,962, dated September 14, 1880.

Application filed July 2, 1880. Term of patent 34 years.

To all whom it may concern:

Be it known that I, WRIGHT SMITH, of the city of Paterson, in the county of Passaic and State of New Jersey, have originated and Designed a Pattern for Handkerchiefs or other Fabrics, of which the following is a clear and exact description, reference being had to the accompanying photographic illustration, making part of this specification.

A represents the center of the handkerchief; B, the border.

The center is composed of reversed twill blocks, of various colors, produced from a striped warp and change filling for each row of blocks across the warp, the blocks being ornamented by raised figures, substantially as shown.

The border B consists of a continuation of the striped warp in the direction of the warp and of the filling in its direction, woven in Florentine twill, and bounded inside and outside by plain satin stripes C C.

What I claim is—

A handkerchief ornamented with the reverse twill-blocked center A and the border B, as shown, woven in Florentine twill, and bounded by the satin stripes C C, all substantially as described, and shown in the accompanying illustration.

WRIGHT SMITH.

Attest:

HUGH SWEENEY,
A. E. GALLANT.
